UNITED STATES PATENT OFFICE.

CAMILLE DE VLEESCHOUWER, OF AMSTERDAM, NETHERLANDS.

AUTOMATIC DOOR-LATCHING DEVICE.

Application filed November 2, 1925, Serial No. 66,357, and in Germany November 6, 1924.

Automatic door latching devices are known especially for double doors, whereby one door being closed, the second door bolts the first door, when said second door is closed.

It is known to provide the door which is first to be closed with a bolting device in such a manner that when closing the second door, the first door is bolted by means of a pin 10 extending from the first door, which is turned by the second door when this door is closed. The pin then transfers its movement to a spring pressed bolt. In these known devices said pin is directly and rigidly connected 15 to the bolt and protrudes through an inclined slot. The door bearing the latching device being closed, the pin extends in the path of the second door which when closed forces the pin up through the inclined slot, 20 whereby the first mentioned door is bolted. The pin moving through the inclined slot, which must have a high pitch, meets with a considerable friction which very soon wears the slot so that the friction is still increased, 25 and at length the door instead of moving the pin, sometimes assumes an inclined position so that the door is not bolted.

According to the invention the transmission of the movement of the pin to the bolt 30 is such that but little friction occurs. The pin is therefore connected to a bellcrank lever pivoted at the frontside of the casing of the latching device, whilst the bolt is connected by means of a connecting link with 35 the bell crank lever. The bolt is guided in two eyes or lugs arranged in the casing so that any stress exerted on the bolt is transferred to the eyes and not to the other mechanism of the latching device.

40 A mode of carrying the invention into effect is illustrated in the accompanying drawings, in which

Fig. 1 is a rear view of the device with inwardly drawn bolt,

45 Fig. 2 is a similar view as illustrated in Fig. 1 but with the bolt extended, and

Fig. 3 is a side view of the device.

In a rectangularly bent strip of metal 1 the bolt 2 is shiftably arranged, the front 50 end of the bolt being guided in an eye in the

part 3 of the strip, and the rear end of the bolt in a cornerpiece 4. The bell crank lever 5 is pivoted about a pin 6, whilst the projecting pin 7 rigidly connected to the bell crank lever protrudes through a slot 8 in the front wall of the metal strip 1.

The bolt is connected by means of a connecting link 9 to the bell crank lever at the point 10.

The bell crank lever is connected by means 60 of a spiral spring 11 to the corner piece 4. The position of the pivot 10 is so chosen with relation to the pivot pin 6, that when the bell crank lever is moved by means of the pin 7, the force is transmitted in a 65 favourable manner to the bolt. It is obvious that but very small frictional resistances occur even when the pivots are not greased which is generally the case in such devices.

What I claim is:

1. A door latching device including an angle attaching plate adapted to be secured to the corner of a door and having a bolt opening in one portion thereof, the other portion being provided with a curved slot 75 opening at one side edge thereof, a bolt slidably mounted on the plate and adapted to be projected through the opening, a bell crank lever pivoted to the plate and operatively connected to the bolt, an actuating 80 pin carried by the lever and projecting through and beyond the slot and operating therein and adapted to be moved out of the slot upon the closing of the door to effect a projection of the bolt, and means for reTRACTING the bolt upon the opening of the door.

2. A door latching device as claimed in claim 1, wherein a link is pivoted at one end to the bell crank lever and at the opposite 90 end to the bolt so as to form the operative connection therebetween, and wherein the means for retracting the bolt includes a coiled spring having one end connected to the bell crank lever adjacent the point of 95 connection of the link and its opposite end connected to the plate, substantially as and for the purposes set forth.

In testimony whereof I affix my signature.

CAMILLE DE VLEESCHOUWER.
